US00D907601S

(12) **United States Design Patent** (10) **Patent No.:** **US D907,601 S**
(45) **Date of Patent:** **** Jan. 12, 2021**

(54) **WIRELESS AUDIO SPEAKER**

(71) Applicant: **Huayuan Yang**, Guangdong (CN)
(72) Inventor: **Huayuan Yang**, Guangdong (CN)
(73) Assignee: **SHENZHEN HAOSHENG TECHNOLOGY CO., LTD**, Shenzhen (CN)

(**) Term: **15 Years**

(21) Appl. No.: **29/744,523**

(22) Filed: **Jul. 29, 2020**

(51) LOC (13) Cl. **14-03**
(52) U.S. Cl.

USPC **D14/216**
